UNITED STATES PATENT OFFICE.

THOMAS SPENCE, OF PHILADELPHIA, PENNSYLVANIA, ASSIGNOR OF ONE-HALF TO
CARLETON E. DAVIS, OF PHILADELPHIA, PENNSYLVANIA.

RECORD-FILING DEVICE.

Application filed March 15, 1922. Serial No. 543,963.

To all whom it may concern:

Be it known that I, THOMAS SPENCE, a citizen of the United States, residing at Philadelphia, in the county of Philadelphia and State of Pennsylvania, have invented 5 certain new and useful Improvements in Record-Filing Devices, of which the following is a specification.

This invention relates to improvements in 10 filing cards for accounts and records of various kinds and in containers for storing them in series.

Heretofore cards of this class have been centrally perforated near the bottom there- 15 of for the reception of a retaining rod, and the containers for storing the cards in series have been provided with rods each of which extended through the perforations of the cards of the series thereof stored within its 20 container and prevented the removal of any card from the series or its change of position within the series. The cards have rested normally on the bottom of the container and were prevented thereby and by 25 the side walls of the container from being turned about the axis of the retaining rod while the rod prevented any card from being raised relatively to the other cards of the series, so that in order to read a card 30 it was necessary to separate the series to provide a space in front of the card to be read and to push back the upper portion thereof until the card being read assumed a slight incline limited by the number of cards 35 back of it and their engagement with the retaining rod. This has been objectionable because the provision of the necessary room for spacing the cards for reading purposes has limited the capacity of the container 40 and because reading has been difficult even when liberal room has been allowed for the separation of the cards on account of the fact that the bottom of the card could not be raised from the bottom of its series with- 45 in the container, and the difficulty has been enhanced when the container has been a low drawer in a cabinet of card-containing drawers.

The object of the invention is to overcome 50 the aforesaid objectionable characteristics and the same is accomplished by the provision of filing cards and a container therefor of novel, simple and efficient construction in which a retaining rod of the container prevents the removal therefrom of

any card of a series and prevents any card from being removed from the series and replaced therein in a wrongful position and permits any card to be raised relatively to the remaining cards of the series and the 60 retaining rod, or turned upwardly about the axis of the rod, or both; and in which the main body of a card may be turned back on a hinge connecting it with an edge portion thereof into a convenient position 65 above the series for reading after first being moved up from its normal position within the series.

With the above object in view, the invention consists in the novel construction, 70 combination and arrangements of parts hereinafter described and claimed.

In the accompanying drawings, illustrating my invention,

Figure 1 is a perspective view of a card- 75 container provided with cards embodying my invention, one of the cards being shown as moved from its normal position within the container to a convenient position for reading.

Figure 2 is a transverse section through the container showing by dotted lines and by dot-and-dash lines two positions of one of the cards away from its normal position within the container. 80

Figure 3 is a transverse section through a container showing a modification of the invention.

Figure 4 is a sectional detail, showing the forward end portion of the retaining rod 90 and a portion of the forward wall of the container.

Figures 5 and 6 are views of the filing cards shown in Figs. 2 and 3, respectively, removed from their containers. 95

Figures 7 and 8 are views of modified forms of filing cards.

Figure 9 is a sectional detail, on line 9—9 of Fig. 5, showing the hinge connection of two parts of a card. 100

Referring to the drawings, 2 designates a series of filing cards and 3 a container therefor.

The container 3 may be of any shape and size for its intended purpose. As herein illustrated, it is in the form of a drawer adapted to be used in a cabinet containing other similar drawers for the storage of cards. The drawer 3 has an open top and it comprises a front wall 4, a bottom wall 105 110

5, side walls 6 and a brace 7 connecting the rearward ends of the side walls 6, all suitably secured together. The bottom wall 5 of the drawer 3 has a longitudinal depression 9 therein in which is secured a guiding plate 10 for a back plate or wall 11 which extends upwardly back of the series of cards 2 to support the same and which is adjustable toward and from the front 10 wall 4 to provide the desired space between the walls 4 and 11 for the number of cards of the series, the wall 11 being adjusted from time to time to increase the space between the front and back walls as more cards are 15 added to the series.

The drawer or container 3 as thus far described is of common and well-known construction and no detailed illustration or description thereof is deemed necessary herein.

20 The cards of the series 2 have horizontal dimensions slightly less than the distance between the side walls 6 of the container and the vertical dimensions of the cards are greater than the distance between the bottom of the container 3 and the top of its side walls 6 so that when the cards 2 rest upon the bottom wall 5 the upper portions thereof will extend above the side walls 6, as clearly shown in the drawings.

30 Each card of the series, as shown in Figs. 1, 2, 5 and 9 comprises a main body portion 12 and a lateral edge portion 13 hingedly connected to the main body portion 12, at 14, by means of a thin strip of tough paper 35 or other suitable material 15 pasted to the backs of the portions or sections 12 and 13 and crossing the joint between them, permitting the body portion 12 to be turned backward on the hinge 14 for a purpose presently appearing; and the edge portion 13 of each card 2 has a vertical slot 16 therein which extends from a point near the top thereof to the central portion thereof, as illustrated.

45 The container 3 is provided with a retaining rod 17 which extends horizontally through the upper end portions of the slots 16 of the entire series of cards 2. The rearward end of the rod 17 rests normally within an opening 18 in a plate or bracket 19 secured to the brace 7 and from which the rod 17 may be withdrawn when desired. The forward end portion of the rod 17 is enlarged and threaded, at 20, and screwed 55 into an opening 21 in the front wall 4 of the container 3. The forward end of the threaded portion 20 terminates in a suitable knob or head 21^a by means of which the rod 17 may be turned to screw the portion 20 thereof into or from the threads of the opening 21, and by means of which the rod 17 may be withdrawn from the openings 16, 18 and 21 and returned thereto when it is desired to remove a card or cards from 60 the series 2 or add a card or cards thereto.

The cards 2 rest normally within the container 3, as shown in Figs. 1 and 2, and when it is desired to read the matter recorded on the forward face of a card, it may be raised relatively to the container 3 and retaining rod 17 and the remainder of the cards of the series to the position shown by dotted lines in Fig. 2, and then turned about the axis of the rod 17 to the position shown by dot-and-dash lines in Fig. 2, 70 bringing the main body portion 12 of the card above the remainder of the series of cards and permitting it to be turned back on its hinge 14 into an upwardly facing position, as shown in Fig. 1, permitting the matter recorded on its face to be conveniently read or additional matter to be conveniently recorded thereon. A reversal of the operation just described will return the card to its normal position in the series of 80 cards within the container. 85

The rod 17 while permitting individual cards to be moved from and returned to the series of cards for reading and recording, as just described, prevents the entire removal of any card from the series and always retains a portion of any card, in any position to which it may be adjusted, either forwardly or back of an adjacent card of the series or between two adjacent cards of the 90 series in the place where it belongs in the series and prevents it from being returned to a wrong position within the series.

In the construction shown in Figs. 3 and 6 the container 3 is provided with two parallel retaining rods 22 which extend through the upper end portions of parallel vertical slots 23 formed in cards 24 near the lateral edges thereof and each card 24 comprises an upper main body portion 25 and a lower edge portion 26 hingedly connected, at 27, to the body portion 25. When it is desired to read or record matter on the forward face of a card 24, it is raised from the full-line position shown in Fig. 3 to the dot-and-dash line position shown therein and thereafter its body portion 25 is turned back on the hinge 27 to face upwardly for convenient reading or recording. 100

In Fig. 7 I have shown a card 12^a which is like the cards shown in Figs. 1, 2, 5 and 9, excepting that a round hole 29 is provided for the reception of the rod 17 instead of the slot 16. To read a card 12^a of a series thereof retained in the container 3 by the rod 17 it is merely necessary to turn the card 28 about the axis of the rod 17 until the main body portion thereof is raised above the remaining cards of its series and then turn it back on its hinge 14 to face upwardly. When the cards 12^a are used, it is necessary to provide sufficient clearance between the edge 30 thereof and the adjacent side wall 6 of the container 3 to 110 permit the card to be turned, as described, 115 120 125 130

or cut the corner 31 from the card 28 on the dot-and-dash line 32.

In Fig. 8 I have shown a card 33 like the cards shown in Figs. 1, 2 and 5 excepting that the body portion 12 and lateral edge portion 13 are formed in a single piece 34 eliminating the hinge 14. When the hinge is thus eliminated, the body of the card 33 may be flexed backward to cause its face to be directed upwardly for reading after first being moved to a position similar to the position of the card shown by dot-and-dash lines in Fig. 2.

I claim as my invention:

- 15 1. A card container having an open top and a retaining rod extending from the front to the rear near one side of the top thereof, in combination with a filing card of a series thereof having substantially a vertically extending slot closed at its top and at its bottom and located near the top and near a lateral edge thereof through which the rod extends, preventing the removal of the card from the rod, said card being free to be moved up and down and turned about the axis of the rod.
- 20 2. A card container having an open top
- 25 and a retaining rod extending from the front to the rear near one side of the top thereof, in combination with a filing card comprising 30 a main body portion and a narrower lateral edge portion hingedly connected thereto and having substantially a vertically extending slot therein through which the rod extends, 35 preventing the removal of the card from the rod, and permitting the card to be moved bodily up and down and turned about the axis of the rod, and permitting the main body portion of the card to be turned on its hinge connection relatively to said edge portion of the card after the card has been 40 raised from a normal position within the container and turned about the axis of the rod.
3. A filing card comprising a main body 45 portion and a narrower vertically extending edge portion hingedly connected thereto and having substantially a vertically extending slot therein for the reception of a retaining rod.

In testimony whereof I affix my signature hereto.

THOMAS SPENCE.
